UNITED STATES PATENT OFFICE.

CLARENCE CARSON, OF DETROIT, MICHIGAN, ASSIGNOR, BY MESNE ASSIGNMENTS,
TO CHRYSLER CORPORATION, A CORPORATION OF DELAWARE.

DESIGN FOR A VEHICLE BODY.

Application filed November 15, 1926. Serial No. 19,727. Term of patent 3½ years.

To all whom it may concern:

Be it known that I, CLARENCE CARSON, a citizen of the United States, residing at Detroit, in the county of Wayne and State of Michigan, have invented a new, original, and ornamental Design for Vehicle Body, of which the following is a specification, reference being had to the accompanying drawing, forming part thereof.

In the drawings:

Figure 1 is a side elevational perspective

view of a vehicle body, showing my new design,

Figure 2 is a top plan view of the same, and

Figures 3 and 4 are front and rear elevational views respectively.

I claim:

The ornamental design for a vehicle body, as shown.

CLARENCE CARSON.
